UNITED STATES PATENT OFFICE

2,484,770

ADJUSTABLE RACK AND PINION GEARING

John H. Worthen, Providence, R. I., assignor to
Federal Products Corporation, a corporation of
Rhode Island

Application October 17, 1944, Serial No. 559,072

1 Claim. (Cl. 74—422)

1

This invention relates to a dial indicator.

A dial indicator of the type referred to consists of a casing and a gear train mechanism within that casing for multiplying and conveying movement of a contact plunger or finger to a hand for moving over a dial. The casing usually provides a front wall which has mounted therein a bearing for the staff upon which the indicating hand is mounted. This bearing is usually carried by this front plate of the casing and remains with this front plate at all times. Thus, when the gear train mechanism is withdrawn the staff is drawn out of this bearing.

Little or no trouble is experienced in this type of mounting when the gears in the gear train are all complete circular gears. However, when segmental gears are used the looseness of the staff when withdrawn from the bearing of the front plate frequently permits many of the gears of the gear train to come out of mesh and considerable difficulty is experienced in the positioning of the gear train mechanism in a casing so that it will properly operate.

One of the objects of this invention is to provide an arrangement so that the gears of the operating mechanism will not become disengaged through handling and prior to or during the assembly of the mechanism in its case.

Another object of this mechanism is to provide a unit which will be substantially complete and will not depend upon any bearing in the casing for the mounting of any part of the mechanism.

Another object of this mechanism is to provide an arrangement completely independent of the dial hand staff for centralizing the gear train mechanism in the casing.

Another object of this invention is to provide an arrangement so that a movement may be had of the gear train mechanism and the operating rack of the casing so that a convenient assembly of the two with the proper meshing of the pinion and rack may be had.

With these and other objects in view, the invention consists of certain novel features of construction, as will be more fully described and particularly pointed out in the appended claim.

In the accompanying drawings:

Fig. 1 is a top plan view of a dial indicator of the type which is the subject of this invention;

Fig. 2 is a section approximately on line 2—2

of Fig. 1 but showing some of the operating parts in full instead of in section;

Fig. 3 is a fragmental detail of one part of the casing;

Fig. 4 is an edge view of the separable unit which is placed in the casing;

Fig. 5 is a plan view of the casing prior to the assembly of the unit therein;

Fig. 6 is a plan view of the unit for assembly in the casing in Fig. 5;

Fig. 7 is a view similar to Fig. 5 but showing the unit of Fig. 6 assembled in the casing with the gearing beneath the plate of the unit dotted to show the relative position thereof.

In proceeding with this invention, I provide a pair of plates held in spaced relation for mounting the complete gear train and dial hand staff for the transmission of motion to the dial indicator. One of these plates is so shaped as to fit snugly with the casing in which it is to be assembled so as to centralize and hold the movement in position therein. The staff for the dial hand has its bearings in the plates and extends through an opening in the front plate of the casing out of contact with the walls thereof.

With reference to the drawings 10 designates generally a casing which consists of a cylindrical side wall 11 and a front wall 12 having an opening 15 therein. A stem 13 having a bore 14 extends from the side walls as shown in Figs. 2 and 5. A back wall or cover 16 fits into a recess 17 in the side wall 11 and is secured in place by screws 18 engaging the threaded openings 19 in the bosses 20 formed integral with the side wall 11.

A plunger 21 is slidably mounted in the bore 14 of the stem 13 and is provided with a rack 22 formed therein. A pin 23 extends from this rack and the plunger is moved outwardly from the casing by a spring 24 which engages the pin 23 and is anchored to one of the bosses 20 or to the securing screw which extends therethrough.

A complete unit designated 25 contains the operating mechanism for the indicator and may be positioned into the casing or taken bodily therefrom. This unit consists of a front plate 26 and a back plate 27. These plates are spaced apart by a plurality of posts 28 held by screws 29 in fixed relation to the plates 26 and 27, which provides a framework in which the movable parts

of the indicator are mounted. A staff 30 is rotatably mounted in both plates in bearings 31 and 32 provided in these plates. These bearings have a press fit with each of the plates and remain as a permanent part of the unit assembly. A gear or pinion 33 is mounted on this staff 30. A segmental gear 34 is mounted on shaft 35 having bearings in the plates and engages the pinion 33. Upon this shaft 35 there is also mounted a pinion 36 so as to rotate with the shaft 35. Another segmental gear 37 mounted on shaft 38 having bearings in the plates meshes with pinion 36 while a pinion 39 is mounted on shaft 38 so as to rotate therewith. The pinion 39 is for engagement with the rack 22 on the plunger 21.

Another segmental gear 40 is mounted on a shaft 41 and this gear also meshes with the pinion 33. A suitable spring 42 acts upon this gear segment tending to rotate the segmental gear and the pinion in one direction, the arrangement being such as to bring the pointer back to zero as well as assisting in returning the gear mechanism to zero and causing the plunger to move out of the casing.

The entire unit 25 is positioned in the casing 44 so that the staff 30 extends through the opening 15 in the front wall 12 thereof. The points 45, 46, 47, 48, of the plate 27, engage the inner surface of the cylindrical wall 11 of the casing so as to locate the unit in a position so that the staff 30 passes through the opening 15 without contact with the edges thereof. In positioning this unit in the casing, pinion 38 will be first located somewhat to the left of the rack 22 and then by turning the unit such as shown in Fig. 6 or 7 counterclockwise, the pinion 39 will be brought into engagement with the rack so that the teeth of the two will properly mesh. Any desired entrance of the teeth one with the other may be obtained by the rotation of the unit 25 in the casing. When this desired amount has been obtained, the casing will be locked in position by pressure of the cover against the unit

forcing the front wall 26 thereof snugly against the front wall 12 of the casing.

After this assembly has been had a suitable dial 50 will be positioned on the front wall 12 of the casing. A dial hand 51 will be provided on the staff 30 and a glass cover or lens 52 mounted in bezel 53 may be positioned over the dial and hand so as to protect the same.

The projection 54 on the rear wall 16 will serve for mounting the dial in suitable location.

It will be readily apparent that with the unit 25 assembled prior to positioning in the casing none of the gears may become dislodged or out of mesh by reason of such positioning. Also by reason of the unit being rotatable to position the pinion into the rack a proper mesh may be had between the parts.

I claim:

A dial indicator comprising a casing, a rack movable in and out of said casing, a unit containing operating mechanism and a pinion to mesh with said rack, said unit comprising a pair of plates one of which fits the inner surfaces of said casing to locate the unit therein and is movable with reference to the casing to cause engagement of said pinion with said rack until the desired mesh of rack and pinion is obtained.
